DESIGN FOR A COMBINED CIGARETTE AND CIGAR HOLDER, ASH TRAY, AND LOUD
SPEAKER

John Douglas Chirite, Detroit, Mich.

Application October 23, 1948, Serial No. 149,256

Term of patent 14 years

(Cl. D85—2)

To all whom it may concern:

Be it known that I, John Douglas Chirite, a citizen of the United States, residing at Detroit, in the county of Wayne and State of Michigan, have invented a new, original, and ornamental Design for Combined Cigarette and Cigar Holder, Ash Tray, and Loud Speaker, of which the following is a specification, reference being had to the accompanying drawings, forming part thereof.

Figure 1 is a perspective view of a combined cigarette and cigar holder, ash tray, and loud speaker, showing my new design;

Fig. 2 is a top plan view thereof;

Fig. 3 is a side elevational view thereof; and

Fig. 4 is a bottom plan view thereof.

I claim:

The ornamental design for a combined cigarette and cigar holder, ash tray, and loud speaker, as shown.

JOHN DOUGLAS CHIRITE.
